UNITED STATES PATENT OFFICE

JOHN FANARJIAN, OF UNION CITY, NEW JERSEY, ASSIGNOR OF ONE-FOURTH TO
JOSEPH F. O'BRIEN, OF ENGLEWOOD, NEW JERSEY

CABINET

Application filed November 29, 1930. Serial No. 498,968.

This invention relates to improvements in cabinets.

One of the objects of this invention is to produce a cabinet, which is provided with a pivoted closure element or section capable of being pivotally swung outwardly from the part of the cabinet on which it is mounted and preferably providing a writing surface or desk and another sliding closure section or element comprising a sliding panel portion of said cabinet and having a sliding connection with said pivotally-swinging section so as to be carried by said pivotally-swinging section in its pivotal or extension movement and also to have a sliding connection with the cabinet for the purpose of closing a section of said cabinet, said parts being so arranged as to cause an automatic locking in closed position of the pivotally-swinging section when the sliding section is moved into closed position.

Still another object of my invention is to mount upon the inner surface of said pivoted element a drawer so as to cause the cabinet, when the pivoted element is opened up, to have all the appearance of a permanent, stable and ornamental desk.

Still another object of my invention is to provide, in combination with a pivoted extensible element of the type described, leg members pivoted to the extensible element and arranged to drop automatically upon the outward swinging of the pivoted element and also to provide a plurality of foot members so connected together as to be movable simultaneously when either one or the other of the two members are actuated to fold.

With these and other objects in view, the invention comprises the combination of members and arrangement of parts so combined as to co-act and cooperate with each other in the performance of the functions and the accomplishment of the results herein contemplated, and comprises in one of its adaptations the species or preferred form illustrated in the accompanying drawings, in which:—

Fig. 1 is a front elevation, in closed position, of a cabinet embodying my invention; 50 Fig. 2 is a similar front elevation of the

cabinet shown in Fig. 1 with the sliding panel in open position;

Fig. 3 is a front elevation of the cabinet shown in Figs. 1 and 2 when my pivoted element is swung into open position; 55

Fig. 4 is a side or end elevation of the cabinet shown in Fig. 3 with the pivoted member in extended position;

Fig. 5 is a view, in side elevation, of the pivoted member removed from the cabinet; 60

Fig. 6 is a view, in front elevation, of the legs or feet folded preparatory to folding the pivoted member;

Fig. 7 is a section on the line 7—7 of Fig. 3, looking in the direction of the arrows; 65

Fig. 8 is a section on the line 8—8 of Fig. 1, looking in the direction of the arrows;

Fig. 9 is a section on the line 9—9 of Fig. 8, looking in the direction of the arrows; and

Fig. 10 is an enlarged view, in front elevation, partially broken away, of the pivotal connection of the pivoted member with the frame of the cabinet at adjacent parts. 70

Referring now to these drawings, which illustrate a preferred embodiment of my invention, my improved cabinet comprises a body portion 1 which, as shown particularly in Figs. 1, 2 and 8, is composed of an oblong box-like structure comprising side wall members 11, 11', a top member 12, a bottom member 13, a back panel 14 and an intermediate inside shelf and bracing member 15 which divides the cabinet into two compartments 1', 1''. The said box-like body portion is provided at the bottom of its forward side with a fixed panel member 16 and, in the embodiment shown, is open above said panel member to the top thereof and this opening is closed by a pivoted extension closure member 2 and a slidable closure member 5. Said pivoted closure member 2, as shown, is provided with pivot elements 3 mounted upon inward extensions 3' and pivoted in the sleeves 4 which are inserted in the side members 11, 11' a sufficient distance from the front surface of the cabinet to compensate for the thickness of a stop bead 5' at the upper edge of the slidable closure panel 5 which, as shown, is slidably mounted in a groove 2' within the pivoted member 2 and is adapted to be slid or

100

5 moved upwardly to provide a closure for the upper compartment 1' and to be moved into closed position along the ways 6, 6' and when so moved along such ways, to have an extension portion 5^a within the groove 2' and thus to cause a locking of the pivoted member 2 in its folded and closed position.

10 In the embodiment of my invention shown, the folding pivoted member 2 comprises a front member 2^a, an intermediate or spacing member 2^b and a rear member 2^c, the front member 2^a and rear member 2^c being spaced apart by the intermediate member so as to form the groove 2' within which the slidable member 5 moves.

15 In said preferred embodiment of my invention, I also preferably mount on the rear of the pivoted member 2 a sliding drawer 7 which is preferably mounted to slide in a box 7'.

20 In said preferred embodiment of my invention, I also preferably provide quick acting means for holding the pivoted or swinging member in extended position and, as illustrated, foldable leg members 8 and 9 are provided with lever mechanism arranged to cause a simultaneous folding of both legs upon the movement of one of the same and also having a connection with the frame of the cabinet 25 and so arranged as to cause an automatic opening of the foldable legs upon the outward extension of the pivoted or swinging member, thus providing a construction in which a mere upward swinging movement of the pivoted member into fully extended position 30 will cause the legs to be automatically moved into supporting position for said extension swinging member.

35 In the preferred form of my invention illustrated, the leg members 8 and 9 are hinged by hinges 8', 9' to the edges of the bottom member of the drawer box 7'. As illustrated, one of said leg members is pivotally connected by a pair of toggle levers 20, 21 with the inner edge of the drawer. As illustrated, one member 20 of said pair of levers 20, 21 is at one end pivotally connected at 20' to the leg member, the other lever being likewise at one end pivotally connected at 21' to the drawer 40 casing or box and the opposite ends of said two members being pivotally connected together to provide a folding arrangement thereof. The other leg member is, in the embodiment shown, provided with a crank lever 50 or arm 22 fixedly connected at 22' and having through the connecting lever 23 a pivotal connection with said levers 20, 21 adjacent to the pivotal connection therebetween. As illustrated, the crank lever 22 is provided with a slot 22^a in which a pin 23^a on the connecting lever 23 is adapted to move. Thus after the pin in its lower position has made a connection which will actuate the levers 20, 21 to cause the folding of the leg member 9, the 55 slot will permit movement of the crank arm 60

relative to the end of the lever 23 in order to enable the complete and facile folding of the leg member 9.

65 In the preferred embodiment of my invention, the inward projections or extensions 3' for the pivot 3 are preferably provided on metallic plates 7^a which, as more particularly shown in Figs. 3, 4 and 5, will form side portions of the drawer box or casing 7'.

70 In the preferred embodiment of my invention, I also provide a finger notch 24 in the fixed panel 16 so as to permit a ready gripping of the lower edge of the swinging extension member 2 and also provide a knob 25 on the head 5' of the sliding panel to enable ready engagement by the hand of the user of the panel and a movement thereof into closed or open position, as desired. Also, in the preferred embodiment of my invention, I provide suitable means for frictionally retaining the sliding panel in its uppermost position and, as illustrated, this is accomplished by mounting in a spring socket 26 a spring 26' which is adapted to engage and force outwardly a ball 27 toward and particularly through a restricted opening so that a surface of said wall will frictionally engage and interlock with a metallic socket 28 formed in one or both of the way members 6, 6'.

75 The operation of the device will be substantially obvious from the above description, it being only necessary to say that, assuming the parts to be in the closed position shown in Fig. 1, a user may grasp the knob 25 and by exerting slight pressure to overcome the locking engagement between the ball 27 and socket 28, move the panel downwardly into the groove 2'. When the parts are in 80 this position, the swinging extension member 80 will be grasped by engagement of the fingers through the notch 24 and this extension member lifted or swung upwardly, whereupon the legs will automatically move downwardly into supporting position for said swinging extension member and in this position it will be noted that the edges 8^a, 9^a, which are suitably reinforced by moldings, will abut against the inset way elements 6, 6' of the cabinet and thus, in connection with the contact of the lower portion of the leg members on the ground, provide a double support for the swinging extension member.

85 When it is desired to close the cabinet, the leg members are, as hereinabove indicated, folded simultaneously by the movement of one of the same into folded position, whereupon the swinging extension member may be dropped into closed position. As shown, the leg member 9 may be engaged and moved upwardly about its hinges. This will cause a simultaneous closing of the other leg member 8 whereupon the swinging extension member 2 may then be swung or dropped, as aforesaid, into closed position. When the swinging member is so moved into closed position 90

sition, the sliding panel member 5 may then be slid upwardly to completely close the cabinet and also, more particularly, simultaneously and automatically to lock the extension swinging member in its closed position, said swinging member being retained in such closed position because the extended lower end of the sliding member never leaves the groove 2' of the swinging member during the 10 closing movement of the sliding member. The swinging member will thus be locked until the sliding panel is again slid down into the groove 2'.

It will be seen from the above that I have 15 provided a cabinet construction having a plurality of compartments, one of which is closed by a swinging extension member adapted to form a desk or the like and the other of which is closed by a sliding panel which, in its closing movement, automatically locks the swinging extension member in its closed position; also that I provide a construction in which the slide member is carried by the swinging member; that the swinging member is pivoted 20 at the inner side of the sliding member so that in closed position the sliding member moves between the outer surface element 2^a and the pivots; that the projections on which the pivots are mounted project a sufficient 25 distance beyond the pivoted edge of the swinging member to compensate or provide a space in extended position for the thickness of a stop bead of the sliding member, and that said stop bead 5' is preferably arranged 30 so that its top surface will be flush with the outer surface of the extension swinging member and with the upper surface of the shelf when the parts are in extended position. Said top surface of the bead will also preferably 35 be provided with the knob 25 engageable by the fingers to slide the panel into open and closed position, as desired.

Having described my invention, I claim:—

1. A cabinet embodying, in combination, a 45 body portion having an opening, a pivoted closure element having a swinging movement to close a part of said opening, and a slideable closure element carried by said pivoted closure element and having a sliding movement to close the balance of said opening.

2. A cabinet embodying, in combination, a body portion having an opening, a pivoted closure element having a swinging movement to close a part of said opening, and a slideable closure element carried by said pivoted 55 element in telescoped relationship and movable to close the balance of said opening, said sliding element having a part adapted in said closed position to remain in telescoping relationship with and automatically to fasten the pivoted element against opening movement when the said slideable element is in closed position.

3. A cabinet embodying, in combination, 60 a body portion having an opening, a closure

element pivoted at one edge, adapted to close a part of said opening and having a pocket open at the edge thereof about which said element swings pivotally, a slideable closure element mounted to slide in said pocket and 70 adapted upon movement out of said pocket to slide into closed position in engagement with the walls of said cabinet opening, said sliding element having a part adapted in said closed position to extend into said 75 pocket and automatically to fasten the pivoted element against opening movement when the said slideable element is in closed position.

4. A cabinet embodying, in combination, a body portion having an opening, a pivoted 80 and vertically swingable closure element adapted to close a part of said opening, and a slideable closure element carried by said pivoted closure element and having a sliding movement to close the balance of said opening, said sliding element having a part adapted in said closed position to extend into and automatically to fasten the pivoted element against opening movement when the said slideable element is in closed position, and 85 means mounted on the inner surface of said vertically swingable element for supporting said element when the same is swung at right angles to the cabinet.

5. A cabinet embodying, in combination, a body portion having an opening, a pivoted 90 and vertically swingable closure element adapted to close a part of said opening, and a slideable closure element carried by said pivoted closure element and having a sliding 100 movement to close the balance of said opening, said sliding element having a part adapted in said closed position to extend into and automatically to fasten the pivoted element against opening movement when the said 105 slideable element is in closed position, a drawer casing mounted on the inner side of said pivoted element, a slideable drawer mounted in said casing, and means for supporting said pivoted element in open position. 110

6. A cabinet embodying, in combination, a body portion having an opening, a pivoted and vertically swingable closure element adapted to close a part of said opening, and a slideable closure element carried by said 115 pivoted closure element and having a sliding movement to close the balance of said opening, said sliding element having a part adapted in said closed position to extend into and automatically to fasten the pivoted element against opening movement when the said slideable element is in closed position, a drawer casing mounted on the inner side of said pivoted element, a slideable drawer mounted in said casing, foldable legs mounted on said casing and adapted upon a movement thereof into full open position to automatically move into supporting position for 120 said pivoted element.

7. A cabinet embodying, in combination, 125

a body portion having an opening, a pivoted and vertically swingable closure element adapted to close a part of said opening, and a slidable closure element carried by said 5 pivoted closure element and having a sliding movement to close the balance of said opening, said sliding element having a part adapted in said closed position to extend into and automatically to fasten the pivoted element against opening movement when the 10 said slidable element is in closed position, a drawer casing mounted on the inner side of said pivoted element, a slidable drawer mounted in said casing, a pair of foldable 15 legs mounted on said casing, and lever mechanism connected with said pivoted element and with said legs to cause both of said legs to be folded simultaneously upon the movement of one thereof.

20 In witness whereof, I have signed my name to the foregoing specification.

JOHN FANARJIAN.
